(57) **CLAIM**

The ornamental design for a solar panel, as shown and described.

DESCRIPTION

FIG. 1 is a front, bottom, and left side perspective view of a first embodiment of a solar panel;

FIG. 2 is a front elevational view thereof;

FIG. 3 is a rear elevational view thereof;

FIG. 4 is a right side elevational view thereof, the left side elevational view being a mirror image of the right side elevational view;

FIG. 5 is a top plan view thereof, the bottom plan view being a mirror image of the top plan view; and

FIG. 6 is an enlarged view of the section indicated by the dot-dash callout box 6 in FIG. 3;

FIG. 7 is a cross-sectional view taken along line 7-7 in FIG. 6;

FIG. 8 is a front, bottom, and left side perspective view of a second embodiment of a solar panel;

FIG. 9 is a front elevational view thereof;

FIG. 10 is a rear elevational view thereof;

FIG. 11 is a right side elevational view thereof, the left side elevational view being a mirror image of the right side elevational view;

FIG. 12 is a top plan view thereof, the bottom plan view being a mirror image of the top plan view;

FIG. 13 is an enlarged view of the section indicated by the dot-dash callout box 13 in FIG. 10; and,

FIG. 14 is a cross-sectional view taken along line 14-14 in FIG. 13.

(Continued)

The evenly spaced broken lines shown in the figures are for the purpose of illustrating portions of the solar panel that form no part of the claimed design. The dot-dash lines in the figures, which form callout boxes and lead lines, form no part of the claimed design.
